(57) **CLAIM**

The ornamental design for a ballast block, as shown and described.

DESCRIPTION

FIG. 1 is a front, top and right side perspective view of a ballast block, showing the new design;

FIG. 2 is a front, bottom and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the Figures are included to show unclaimed subject matter only and form no part of the claimed design.

1 Claim, 6 Drawing Sheets(56)
